UNITED STATES PATENT OFFICE.

JOSEPH STRNISTE, OF WESTFIELD, MASSACHUSETTS, ASSIGNOR TO WESTFIELD MANUFACTURING COMPANY, A CORPORATION OF MASSACHUSETTS.

ROCKING PEDICAR.

Application filed April 19, 1922. Serial No. 555,613.

To all whom it may concern:

Be it known that I, JOSEPH STRNISTE, citizen of the United States, residing at Westfield, in the county of Hampden and 5 State of Massachusetts, have invented new and useful Improvements in Rocking Pedicars, of which the following is a specification.

This invention relates to a child's amusement device and particularly to a new and improved type of rocking device for a child which has some of the characteristics of the well-known pedi-car.

Among the objects of the invention is to 10 provide a toy of this class which is simple in design, easy and inexpensive to construct, and one which is practically indestructible owing to the character of the material of which it is made.

20 Further objects and advantages of the invention will become apparent from the following description and accompanying drawings which illustrate the preferred embodiment of the invention and in 25 which;—

Fig. 1 is a plan view of the device;

Fig. 2 is a side elevation of the same;

Fig. 3 is a front elevation of Fig. 1 and Fig. 2;

30 Fig. 4 is a side elevation of a portion of the device showing method of securing the seat supports to the base.

Fig. 5 is a cross section taken on the line 5—5 of Fig. 4; and

35 Fig. 6 is a front elevation of a portion of the front bracket showing the foot rests.

Referring to the drawings, 1, 1 represents parallel rockers spaced apart whose ends are bent inwardly towards and joined to each 40 other forming end portions 2, 2 continuous with the rockers 1, 1. The portions 2, 2 are bent preferably so that they are circular in form as shown in Fig. 1 and form curved ends for the rockers 1, 1. The curved end 45 portions 2, 2 are also formed so as to lie in substantially the same curved plane which passes lengthwise through the rockers 1, 1 as shown in Fig. 2, or in other words the rocking frame, consisting of the rockers 1, 1 and end portions 2, 2 has a curved rocking 50 tread from end to end. This rocking frame is preferably constructed of tubing and may be made in one or more pieces joined together in any suitable manner such 55 as by a brazed or welded joint. Forming

the rocking frame in this manner saves considerable material without shortening the rocking limits and eliminates corners and sharp points which are usual on devices of this character.

60 A saddle seat 3 shaped in conformity with the well-known pedi-car seat having a narrowed front portion and widened rear portion is supported upon the rockers 1, 1 by a front bracket 4 and rear bracket 5, secured to the under side of the seat in any suitable manner and preferably made of strap iron. In the preferred embodiment the front bracket 4 is provided with arms 12, 12 extending vertically downwardly 65 from the sides of the front end of seat 3 and then horizontally outwardly to the rockers 1, 1. The ends of the arms 12, 12 are bent at right angles to their horizontal portions as shown in Fig. 6, to connect with the 70 rockers 1, 1 in a manner to be presently described. The rear bracket 5 is similar in construction having arms 13, 13 inclining downwardly and rearwardly from the sides of the rear end of seat 3 and connected to 75 the rockers 1, 1 in the same manner. One or more horizontal braces 6 (only one being shown in the preferred embodiment of the invention) extend between the rockers 1, 1 intermediate the front and rear brackets 4 80 and 5 having its ends bent in the same manner as the ends of front bracket 4 and secured to the rockers 1, 1 in the same way.

85 The front and rear brackets 4 and 5 and brace 6 being preferably constructed of 90 strap iron, their ends are securely fastened to the rockers 1, 1 by means of slots 7 provided in the upper side of the tubular rockers. These ends are inserted in the slots 7 and are then welded or brazed to the tubing 95 as shown in Fig. 4 and 5 and are thereby firmly anchored to same.

The construction of the front bracket 4 with its narrow upper portion supporting the front end of the seat and its wider lower 100 portion formed by the horizontally outwardly extending arms connected to the rockers, is such that the horizontally extending portions of the arms 12, 12 form foot rests for the child. If the child's legs 105 are too short to reach these arms, additional foot rests 10, 10 may be provided on the downwardly extending portion of the arms as shown in Fig. 6. These foot rests 10, 10 are adjustably secured to the arms 12, 12 in 110

any suitable manner as by a series of holes 11, 11 through which the threaded ends of the foot rests extend for engagement with a nut.

5 A rigid post 8 carrying a cross-piece 9, adjacent the front end of the saddle seat is preferably mounted on the latter and serves as a handle bar within convenient reach of a child sitting on the seat. In the preferred 10 form shown, the post 8 has a reduced lower end 14 extending through the front end of the saddle seat 3 and the bracket 4, and screw-threaded to receive a nut 15 whereby all of said parts are securely clamped together.

15 It will be observed that a child's toy has been designed which is novel in its construction and which combines features that arouse unusual interest in the child. Its 20 design permits of very rigid construction, and great durability.

25 What I claim is:—

1. A rocking pedi-car comprising in combination a flat saddle seat, a rigid handle bar mounted adjacent the forward end thereof, a rocking frame comprising parallel rockers curvedly converging at the front and rear ends thereof, said rocking frame having a curved rocking tread from end to end, 30 brackets at the front and rear ends of said saddle seat for supporting same from said rocking frame.

35 2. A rocking pedi-car comprising in combination a flat saddle seat, a rigid handle bar mounted adjacent the forward end thereof, a rocking frame comprising parallel rockers curvedly converging at the front and rear ends thereof, said rocking frame having a curved rocking tread from end to end, 40 brackets at the front and rear ends of said saddle seat for supporting same from said rocking frame, and a horizontal brace intermediate said front and rear brackets for connecting said rockers.

45 3. A rocking pedi-car comprising in combination, a rocking frame having parallel rockers, a bracket mounted on one end of said frame and having a narrow upper portion and a wider lower portion and horizontally offset portions connecting first two said 50 portions to serve as foot rests, a second bracket mounted on the other end of said frame, a seat having a narrow portion supported upon said narrow portion of said first bracket and a wide portion supported upon said other bracket, and a rigid handle

bar mounted in said narrow portion of said seat.

4. A rocking pedi-car comprising, in combination, a rocking frame having parallel 60 rockers, a bracket mounted on one end of said frame and having a narrow upper portion and a wider lower portion and horizontally offset portions connecting first two said portions, a second bracket mounted on the 65 other end of said frame, a seat having a narrow portion supported upon said narrow portion of said front bracket, and a wide portion supported upon said other bracket, a rigid handle bar mounted in said narrow 70 portion of said seat, and adjustable foot rests on said first bracket.

5. A rocking pedi-car comprising in combination a flat saddle seat, a rigid handle bar mounted adjacent the forward end of 75 said saddle seat, a rocking frame comprising parallel tubular rockers curvedly converging together at the front and rear ends thereof, said rocking frame having a curved rocking 80 tread from end to end, front and rear brackets for supporting said saddle seat from said frame, said front bracket formed of strap metal bent into a narrow upper portion for attachment to the forward end of said saddle seat, and wider lower portion having ends 85 anchored in said tubular rockers, said rear bracket formed of strap metal with its lower ends anchored in said tubular rockers and converging upwardly for attachment to said saddle seat and an intermediate horizontal 90 brace connecting said tubular rockers.

6. A rocking pedi-car comprising in combination, a rocking frame having parallel rockers, a bracket mounted on one end of said frame and having a narrow upper portion and a wider lower portion and horizontally offset portions connecting just two said 95 portions to serve as foot rests, a second bracket mounted on the other end of said frame, a seat having a narrow portion supported upon the said narrow portion of said first bracket and a wide portion supported upon said other bracket and a rigid handle bar mounted in said narrow portion of said seat comprising a vertical post extending through said seat and upper portion of said first named bracket and provided with means for clamping said bracket and seat securely together.

100 In testimony whereof I have affixed my 110 signature.

JOSEPH STRNISTE.
